INNER AND OUTER ADJUSTABLE ARCH SHOE

Henry A. Kohlruss, Twin Falls, Idaho

Application June 13, 1938, Serial No. 213,508

1 Claim. (Cl. 36—71)

This invention relates to arch supports, and its general object is to provide an adjustable support for various parts of the foot, such as the heel, the metatarsal arch, and the longitudinal arch, and the support is capable of being adjusted with respect to each of the various parts, so as to support the same in the proper manner, to bring about correction thereof and utmost comfort to the wearer.

10 A further object is to provide a support that can be readily adjusted to any height, while the shoe is on the foot of the wearer, so that proper adjustment will be assured.

Another object is to provide a support that can be adjusted in an easy and expeditious manner, is simple in construction, inexpensive to manufacture and extremely efficient in use, operation and service.

20 This invention also consists in certain other features of construction and in the combination and arrangement of the several parts, to be hereinafter fully described, illustrated in the accompanying drawing and specifically pointed out in the appended claim.

25 In describing the invention in detail, reference will be had to the accompanying drawing wherein like characters denote like or corresponding parts throughout the several views, and in which:

30 Figure 1 is a view partly in section, illustrating my support within a shoe, and with the supporting members thereof in neutral or their lowermost position.

Figure 2 is a similar view with the supporting means in partly raised position.

35 Figure 3 is a perspective view illustrating the supporting members in dotted lines.

Figure 4 is a sectional view taken approximately on line 4—4 of Figure 1.

40 Figure 5 is a detail view of one form of tool or key for the purpose of adjusting the supporting members.

45 Referring to the drawing in detail, it will be noted that my support is attached directly to the shoe, to form a permanent part thereof, and the shoe includes the usual outer sole A and heel B. It will be obvious that the shoe can be built especially for my support or the latter can be applied to any shoe, as no special construction of shoe is necessary, with the single exception that the outer sole thereof is bored to provide openings therethrough, for a purpose which will be later described. The usual insole, not shown, can be used if desired.

50 The support as shown includes three support-

ing members or plates formed from metal or any material suitable for the purpose, and which are indicated respectively by the reference numerals 1 to 3 inclusive, the plate 1 being arranged at the heel of the shoe, the plate 3 for disposal below the metatarsal arch, and the plate 2 below the longitudinal arch. The heel plate is of an outline similar to that of the heel of the shoe, the metatarsal arch plate is of elongated oval outline, while the longitudinal arch plate is of 10 substantially circular outline, and each plate is provided with a flat undersurface and a convex uppersurface, as well as a substantially sharp edge disposed about the entire outline thereof.

15 The outer sole as well as the heel has openings 4 therethrough arranged to underlie the plates, and each opening has a sleeve 5 mounted therein, the sleeves being of identical construction and of a size for fitting the openings. The sleeves are 20 interiorly threaded and each has an annular flange 6 formed on the upper ends thereof and which are countersunk in the sole and heel, as shown. The lower ends of the sleeves are exteriorly threaded to receive ring nuts 7 which are likewise countersunk in the sole and the heel 25 and cooperate with the flanges 6 for fixing the sleeves within the openings, as will be apparent.

30 Threadedly mounted in the sleeves 5 are screw members 8 in the form of bolts that have beveled heads 9 swiveled in the supporting plates, as best shown in Figure 4, and the lower ends of the bolts or screw members 8 are slotted to provide kerfs 10 for the purpose of receiving a tool, such as a key 11 as shown in Figure 5, for raising and lowering the supporting members to their various adjusted position.

35 The supporting members have riveted or otherwise secured thereto a flexible member 12 in the form of an insole which may be made from sheet metal, leather or other material suitable for the purpose, and if desired the usual insole can be disposed to overlie the flexible member, especially if the latter is formed from metal.

40 From the above description and disclosure of the drawing, it will be obvious that I have provided a support secured within the shoe with respect to the heel, the metatarsal arch and the longitudinal arch and which can be readily adjusted to any height desired by a tool or the key as shown in Figure 5 in an easy and expeditious 45 manner, while the shoe is on the foot of the wearer.

45 While I have illustrated a support including connected supporting members, one for each part of the foot mentioned, it will be obvious that the 50

support can be made to include one or two supporting members, with the flexible member 12 secured thereto. However, when they are used collectively, they cooperate to properly support 5 the foot in its entirety.

It is thought from the foregoing description that the advantages and novel features of the invention will be readily apparent.

It is to be understood that changes may be 10 made in the construction and in the combination and arrangement of the several parts, provided that such changes fall within the scope of the appended claim.

What I claim is:

15 A foot arch and heel support for a shoe, comprising plates providing supporting members, one for disposal below the heel, one below the metatarsal arch and one below the longitudinal arch, the heel plate being of an outline similar to that 20 of the heel of the shoe, the metatarsal arch plate being of elongated oval outline, and the longi-

tudinal arch plate being of substantially circular outline, each plate having a flat undersurface and a convex upper surface, the latter providing a marginal feathered edge, means for individually raising and lowering the plates and the means for each plate including a sleeve mounted in an opening in the shoe centrally of and below its plate, the sleeve being interiorly threaded, an annular flange formed on the upper end of the sleeve, a ring nut threaded on the lower end thereof and cooperating with the flange for securing the sleeve to the shoe, said flange and nut being countersunk in the shoe, a screw member for each plate and having a beveled head embedded and swiveled in its plate, said screw member being threaded in the sleeve and having a kerfed lower end for receiving a tool, and a flexible member riveted to the plates and overlying the same.

HENRY A. KOHLRUSS. 20
